UNITED STATES PATENT OFFICE.

CLARENCE E. BOWE, OF HURON, SOUTH DAKOTA.

EXPANSION-DRILL.

SPECIFICATION forming part of Letters Patent No. 434,241, dated August 12, 1890.

Application filed April 24, 1890. Serial No. 349,383. (No model.)

To all whom it may concern:

Be it known that I, CLARENCE E. BOWE, a citizen of the United States, and a resident of Huron, in the county of Beadle and State of 5 South Dakota, have invented certain new and useful Improvements in Expansion-Drills; and I do declare the following to be a full, clear, and exact description of the invention, such as will enable others skilled in the art to which 10 it appertains to make and use the same, reference being had to the accompanying drawings, and to letters of reference marked thereon, which form a part of this specification.

Figure 1 is a side elevation of my improved 15 drill. Fig. 2 is a sectional elevation thereof, one of the bits being removed by the section. Fig. 3 is a view of the same, taken at right angles to the plane of the aforesaid figure. Fig. 4 is a bottom view of my invention, the 20 bits being extended; and Fig. 5 is a modification thereof.

This invention relates to certain improvements in well-drills, particularly expansion-drills; and it consists in the construction and 25 novel combination of parts, as will appear from the following description and accompanying drawings.

In the drawings, A is the holder, which is not perfectly cylindric, having segments, as 30 at a, removed from opposite sides, thus providing for the upward passage alongside thereof of the water through the well. The holder A is screw-threaded upon its inner surface to provide for its ready connection 35 to the manipulating-rod. (Not shown.)

B B are the drills or bits, which are provided with cutting lips or edges b, standing at right angles to the other portions of the lower beveled edge b', while their shanks b² are 40 let into the holder A, each being of a peculiar construction and engaging a corresponding groove c in said holder. The shanks b² are tapered to a point at their inner ends and have one edge convex, as at b³, extending to the right-angled lower edges, while their opposite edges are concave, as at b⁴, the greater portion thereof, the remaining portion being inclined inward and downward, as at b⁵. In each shank is a short curved slot b⁶, corresponding to the 45 curvature of the shank and receiving a cross-pin d in the holder A, limiting the movement of the bits or drills and retaining them in place therein. It will therefore be seen that

when the holder with the bits or drills are in the pipe through which they work they will 55 not be extended or moved laterally; but after leaving said pipe and coming in contact at their cutting-edges with the bottom of the hole or well said bits or drills will then be moved laterally as they cut their way through 60 the earth or surface. This enlargement of the cutting of the earth or surface provides for the reception of not only the pipe, but also the coupling between the pipe-sections.

In the modification as disclosed in Fig. 5 65 the slots in the shanks of the bits or drills are extended, their extensions being provided with springs e, bearing against the cross-pin d and the inner ends of said slot-extensions. Thus the drills or bits will normally press against the sides of the pipe, and consequently the moment they pass the lower end of said pipe be automatically expanded, the expansion being affected by the action of 70 said spring and not by contact of the bits or 75 drills with the earth or surface, as in the other case.

Having described this invention, what I claim, and desire to secure by Letters Patent, is— 80

1. In a well or boring auger, the holder provided with expansible bits or drills the shanks of which are concave on one edge and convex on the other edge and provided with curved slots engaged by a cross-pin in said 85 holder, and springs arranged to act upon said bits or drills to expand the same beyond the holder, substantially as set forth.

2. In a well or boring auger, the combination, with the holder, of the drills or bits 90 having the cutting lips or edges standing at right angles to the other portion of the lower edge thereof and having their shank portions standing at right angles about to the cutting-lips and provided with opposite convex and 95 concave side edges and with curved slots receiving a cross-pin of the holder, said holder having opposite grooves receiving and conforming in shape to said shanks of the bits or drills, substantially as set forth. 100

In testimony whereof I affix my signature in presence of two witnesses.

CLARENCE E. BOWE.

Witnesses:

W. C. ELSON,
C. M. HARRISON.
